[57] CLAIM

The ornamental design for a hanger for use with a partition, as shown and described.

DESCRIPTION

FIGS. 1 and 2 are respectively top and bottom plan views of a hanger for use with a partition showing my new design;

FIGS. 3 and 4 are respectively front and rear elevational views thereof;

FIG. 5 is a left side elevational view thereof, the side opposite being a mirror image;

FIG. 6 is a perspective view taken from above and to one side thereof; and

FIG. 7 is a perspective view taken from below and to the opposite side.

FIG. 1.

FIG. 2.

FIG. 3.

FIG. 4.

FIG. 5.

FIG. 7
